COMBINED ICE MAKING MACHINE AND BEVERAGE DISPENSER OR THE LIKE

James Robert Reichow, Edina, Minn., assignor to The
Cornelius Company, Anoka, Minn., a corporation of
Minnesota

Filed June 15, 1962, Ser. No. 70,557

Term of patent 14 years

(Cl. D67—4)

FIG. 2

FIGURE 1 is a perspective view of a combined ice making machine and beverage dispenser or the like showing my design.

FIGURE 2 is a plan view thereof.

FIGURE 3 is a front elevational view thereof.

FIGURE 4 is a rear elevational view thereof.

FIGURE 5 is a side elevational view thereof.

The dominant features of my design reside in the portions shown in full lines.

I claim:

The ornamental design for a combined ice making machine and a beverage dispenser or the like, substantially as shown and described.
